UNITED STATES PATENT OFFICE

HOMER A. ANDERSON, OF BROOKLYN, NEW YORK

RADIO APPARATUS

Application filed March 10, 1930. Serial No. 434,649.

This invention appertains to improvements in radio apparatus generally, and has for its main object to provide a receiving circuit characterized by extreme sensitivity in reception of each assigned frequency in the present broadcast band of frequencies, maximum selectivity of the different assigned broadcast frequencies, substantially perfect range full tonal reproduction and maximum elimination of interference.

Another object of the invention is to provide a means to effect an increase in the received broadcast signal strength in the primary or antenna circuit of the improved hook-up, whereby the efficiency in operation of both the radio and audio frequency amplifying net-works is correspondingly increased.

Still another object of the invention resides in the provision of a means to so sharpen the received broadcast signal of increased strength at the radio frequency side of the hook-up that the extreme selectivity and perfect tonal reproduction as aforesaid is obtained.

A further object of the invention has to do with the tuning of the received broadcast signal to a point of substantially perfect elimination of interference of all kinds immediately upon the increasing of its natural or normal strength and as it is passed in and through the radio frequency amplifying net-work.

A still further object of the invention lies in the combining of the grid and plate circuits of the radio frequency amplifying net-work into a substantially single circuit which functions as a by-pass or filter to interference frequencies, such as those produced by transmitting stations whose signals it is not desired to receive and by strays, static and the like, while the selected broadcast signal frequency passes directly to the functioning side of the said net-work.

Another object of the invention resides in the by-pass circuit aforesaid being arranged to filter the interfering frequencies past the radio receiving amplifier and to ground before detection and, in the case of several stages of such amplification being employed,

the by-pass or filter circuit will be grounded immediately following each stage thereof.

A further object of the invention is to provide adjustable condensers between the grid and plate electrodes of each of the tubes of the radio frequency amplifying net-work and of the detector located between the said net-work and the audio frequency amplifying net-work, whereby to effect the desired sharpness in tuning of the hookup as a whole, as well as to provide the by-pass circuit aforesaid for the elimination of the interference frequencies to ground.

Another object of the invention is presented in the provision of adjustable condensers connected across the primary and secondary windings of the transformers employed in the radio frequency amplifying net-work, which function to prevent the transference through the transformers to local and static interference.

Still another object of the invention has to do with the provision of adjustable resistance, such as Bradleystats or the like, together with fixed condensers, in the grid circuits of each of the tubes employed in the audio frequency amplifying net-work, in order that such interfering frequencies, particularly those of a popping and crackling nature will be separated from the amplified and detected broadcast signal and by-passed to ground before reaching the output side of the net-work.

With the foregoing and other equally important objects and advantages in view, the invention resides in the certain new and useful hook-up of radio instrumentalities as will be hereinafter more fully described, set forth in the appended claims and illustrated in the accompanying drawing.

Referring to the drawing, wherein a practical embodiment of the invention is depicted diagrammatically by way of example only, the primary circuit of the hook-up is constituted in an antenna 1, which is connected to a ground 2 through the primary winding 3' of an inductive coupling 3, the secondary winding 3'' of the latter being arranged in the input side of the first stage of a radio frequency amplifying net-work. An ad-

justable condenser 4 is connected between the antenna 1, at a point immediately above the primary winding 3', and the lower side of the secondary winding 3'' of the inductive coupling 3 and from thence direct to a ground 5 which has the effect of increasing the strength of the broadcast signal absorbed by the antenna 1.

By this arrangement of the primary winding 3', between the antenna and ground, the same functions somewhat as a choke coil to pass low interfering frequencies to ground, as will be hereinafter fully explained.

In addition to the tuned effect given to the primary or antenna circuit by the condenser 4, the same is to be selectively tuned by means of a variable capacitance 6 which is shunted across the terminals of the secondary winding 3'' of the inductive coupling 3.

In the present instance of the invention, three stages each of radio and audio frequency amplification are employed, with a detector circuit interposed between the output side of the last stage of the former and the first stage of the latter and the tubes of each amplifying net-work are connected in cascade by suitable couplings. As shown, the radio frequency amplifying net-work including the tubes RF1, RF2 and RF3, which are preferably all of the -26 type; the detector circuit a tube D of the -27 type; and the audio frequency net-work the tubes AF1, AF2 and AF3 of which AF1 and AF2 are of the -26 type and AF3 of the -71A type.

The radio frequency amplifier tubes RF1, RF2 and RF3 are coupled in cascade by transformers RT1 and RT2 and RT3 and the detector tube D and the audio frequency amplifier tubes AF1 and AF2 and AF3 by the transformers AT1, AT2, and AT3. The upper terminals of each of the primary windings P, of each of the radio and audio frequency transformers are directly connected to the plate or anode of the tube immediately preceding the same, while the similar terminals of each secondary winding S is directly connected to the grid g of the amplifier immediately adjacent thereto, except that a combined grid condenser GC and grid leak GL unit is interposed between the secondary S of the last stage radio frequency transformer RT3 and the grid g of the detector tube D.

The lower terminals of the primary windings P of both sets of transformers RT1, RT2 and RT3 and AT1, AT2 and AT3 are connected to a common lead 7 from the positive side of the "B" current source, while the similar terminals of the secondary windings S are all connected to grounds 8. The output side of the primary or antenna circuit, i. e., the upper terminals of the secondary winding 3'', of the inductive coupling 3 and the variable capacitance 6, is connected directly to

the grid g of the first radio frequency amplifying tube RF1, from whence a selected broadcast signal will pass successively from stage to stage of radio frequency amplification, by way of the tubes RF1, RF2 and RF3 and the associated transformers RT1, RT2 and RT3 to the detector tube D, while all interfering frequencies will be separated out therefrom and passed to ground as will be now fully explained.

This separating out of interfering frequencies from the selected broadcast signal frequency and the subsequent elimination of the same by being shunted around the several radio frequency amplifying tubes RF1, RF2 and RF3, the detector tube D and the radio frequency transformers RT1, RT2 and RT3 to the grounds 8 is effectively accomplished by the interposing of adjustable condensers c, c¹, c² and c³, respectively, between the grid g and the plate p of each of the radio frequency amplifier tubes and bridging the upper terminals of the associated transformers with similar condensers C, C¹ and C².

The tuning of the second and third stages of radio frequency amplification and the detector circuit is effected by associated variable condensers VC¹, VC² and VC³ respectively, which are connected between the grid 95 and the detector tube D and the lead 9 from the negative side "B" current source. In order to sharpen the tuning of the detector circuit, an adjustable condenser 10 is connected at that side of the variable condenser VC², which is connected to the grid circuit of the detector tube D, and in shunt about the same to ground 10'.

The filaments f of all of the several radio and audio frequency amplifying tubes, as well as that of the detector tube D, are connected to the positive and negative leads 11 and 12 of the "A" current source, substantially as shown.

The elimination of interferences from the selected and amplified broadcast signal frequency is continued after detection and during its transference to and through the audio amplifying tubes AF1, AF2 and AF3 and the associated transformers AT1, AT2 and AT3 by the lower sides of the secondary windings S of the latter being connected to the grounds 8. Here, the interference frequency by-pass circuit around the three stages of radio frequency amplification and the detector tube D terminates with the connection of the grid circuit of the latter tube to the upper side of the variable condensers VC³ and the shunted adjustable condenser 10, 125 which have the lower sides of the same connected to the ground, the condenser VC³ to the ground 9' of the negative "B" current lead 9 and the condenser 10 to its associated ground 10'.

From this point on through the several stages of audio frequency amplification the interference will be, in the main, largely of the local and static type, generally evident by so-called popping and crackling noises or sounds, and this is effectively eliminated by way of the grounds 8, to which the lower sides of the secondary winding S of the audio frequency transformers AT1, AT2 and AT3 are connected. This elimination of the interferences is aided by the connecting of variable resistances VR1, VR2 and VR3 in series with companion adjustable condensers 13, 14 and 15, and between the grid circuits 15 of the tubes AF1, AF2 and AF3 and the ground 9' of the negative "B" current lead 9.

The plate p of the last audio frequency amplifying tube AF3 is connected by a lead 16 to one terminal of the primary winding P of the final audio frequency transformer AT4 which has its other terminal connected, as at 17, to the positive "B" current lead 7. The secondary winding S of the transformer AT4 outputs the purified selected and amplified broadcast signal frequency to a loud speaker or the like (not shown).

In order to finally clarify the selected and amplified broadcast signal frequency, and prior to its reception at the loud speaker, a variable resistance VR4, arranged in series with an adjustable condenser 18 is shunted across the output leads from the secondary winding S of the transformer AT4.

The V27 type of detector tube D is preferably employed because of the fact that it functions with less noticeable hum in the output than do all other types of tubes suitable for use as detectors.

In placing the receiver in use, after the completion of the hook-up, the condenser 4 will be adjustable to initially tune the primary or antenna circuit to a given broadcast signal frequency. Thus, by adjusting this condenser to the capacity of the lowest frequency division of the present broadcasting band of frequencies, the several higher divisions throughout the band range will be capable of pick up and subsequent separation upon the adjustment of the other capacitance controls of the hook-up. After the adjustment of the primary or antenna circuit, the adjustable condensers c , c^1 c^2 and c^3 bridging the grid g and plate p circuits of the radio frequency amplifying tubes RF1, RF2 and RF3 and of the detector tube D will be adjusted successively to points where any incoming interferences will be reduced to an absolute minimum if not totally eliminated. Similarly, the adjustable condensers C , C^1 and C^2 , bridging the upper of the terminals of the primary and secondary windings P and S of the radio frequency transformers RT1, RT2, and RT3 will be adjusted to further the interference elimination.

Likewise the resistors or Bradleystats

VR1, VR2 and V3 together with their companion condensers 13, 14 and 15, will be adjusted to similarly reduce the interferences, tending to pass to the output, to absolute minimum effect or total elimination. Finally, the resistor or Bradleystat VR4 and its companion condenser 18 will likewise be adjusted to a point of absorption of any interferences which might be picked up in the secondary winding S of the last audio frequency transformer AT4.

Thus, with the condensers connected in line throughout the radio amplifying and detector network, low interfering frequencies will be blocked out, while the higher signal frequencies will readily pass along this route to the audio amplifying network. Similarly, the low frequencies will be readily gotten rid of by passing to ground, after each stage of radio amplification and the stage of detection, by way of the secondary windings S of the transformers RT¹, RT² and RT³ and AT¹, which windings also act as choke coils to block out the higher frequencies.

Having thus filtered out interferences from the primary circuit and those getting by the successive stages of radio amplification and the detector stage, other interfering currents of frequencies of lower value, at least as compared to that of the amplified signal frequency, will be readily passed to ground through the resistors or Bradleystats following the detector stage and each of the several stages of audio amplification, while the purified signal current of high frequency will be blocked out thereby and will be passed directly to the output side of the audio amplifying network.

In the receiver shown, the condensers C and c (general designation) within the radio frequency range are of a sufficient capacity, say .0005 microfarad, to let any amount of current through that will allow the receiver to perform with clearness in tonal reproduction and, at the same time, by-pass the undesired frequencies to be checked from passing through the tubes and amplified in the circuit. The condensers 13, 14 and 15, within the audio frequency range may be from one-half to one microfarad, with the Bradleystats VR¹, VR², and VR³, in series therewith, adjusted to take out interferences, regardless how severe, to a minimum and un-noticeable degree. The condenser 18, in the output circuit, will preferably have a capacity of two microfarads.

It is to be especially noted that the radio frequency transformers RT1, RT2 and RT3 are connected in the net-work with "A" and "B" currents connected on the extreme or outside ends of the windings, while the grid and plate circuits are side by side, in which arrangement, sharper tuning is obtained than would be the case with the usual reverse manner of hook-up of these transformers.

Without further description, it is thought that the features and advantages of the invention will be readily apparent to those skilled in the art, and it will of course be

5 understood that changes in the circuit connections and in the type and value of the instrumentalities employed may be resorted to, without departing from the spirit of the invention or its scope as claimed.

10 I claim:

1. A tuned antenna circuit comprising an aerial, an inductive coupling having its primary winding interposed between the input

15 end of the aerial and the ground, a fixed capacitance interposed between the input end of the aerial and the lower side of the secondary winding of the inductive coupling whereby to function in shunted relation with respect to the said primary winding and a

20 ground connection leading from the connected adjacent sides of said condenser and the said secondary winding.

2. A tuned antenna circuit comprising an aerial, an inductive coupling having its primary winding interposed between the input end of the aerial and the ground, an adjustably fixed capacitance interposed between the input end of the aerial and the lower side of the secondary winding of the inductive coupling whereby to function in shunted relation with respect to the said primary winding and a ground connection leading from the connected adjacent sides of the said condenser and the said secondary winding.

3. In a radio receiver circuit including a radio frequency amplifying net-work, a tuned antenna circuit comprising an aerial, an inductive coupling having its primary winding interposed between the input end of the aerial

40 and the ground and the upper side of its secondary winding connected to the grid circuit of the said amplifying network, a variable capacitance interposed between the grid connected side of the secondary winding and the ground, an adjustably fixed capacitance interposed between the input end of the aerial

45 above the said primary winding and the lower side of the said secondary winding whereby to function in shunted relation with respect

50 to the said primary winding, and a connection between the latter connected sides of the adjustably fixed capacitance and the said secondary winding and the ground.

4. A radio receiving system including a radio frequency amplifying network consisting of a plurality of inductively coupled stages, capacitative by-pass means coupled between the input and output circuits of each stage and between the inductive couplings

55 thereof, and means including a reactance coupling said by-pass means to ground.

5. A radio receiving system including a plurality of inductively coupled stages of radio frequency amplification and a stage of detection inductively coupled to the output side of

the last of the said amplification stages, a capacitative by-pass means coupled between the input and output circuits of each of the said amplification stages and of the said detection stage and between the inductive couplings thereof, and means including a reactance coupling said by-pass means to ground at the output side of the said detection stage.

6. A radio receiving system including a stage of inductively coupled radio frequency amplification and a stage of detection inductively coupled to the output side of the said amplifying stage, capacitative by-pass means coupled between the input and output circuits of the said amplifying stage and between the inductive coupling of the same and that of the said detection stage, and means including a reactance coupling said by-pass means to ground.

7. A radio receiving system including a radio frequency amplifying network consisting of a plurality of inductively coupled stages, capacitative by-pass means coupled between the input and out-put circuits of each stage and between the inductive couplings thereof, and a plurality of means each including a reactance coupling said by-pass means to ground.

8. A radio receiving system including a radio frequency amplifying network consisting of a plurality of inductively coupled stages, capacitative by-pass means coupled between the input and output circuits of each stage and between the inductive couplings thereof, and a means including a reactance coupling each by-pass means to ground.

9. A radio receiving system including a radio frequency amplifying network consisting of a plurality of inductively coupled stages and a stage of detection inductively coupled to the output side of the last amplification stage, capacitative by-pass means coupled between the input and output circuits of each amplifying stage and between the inductive couplings between the same and that of the said detection stage, and means including a reactance coupling said by-pass means to ground.

10. A radio receiving system including radio and audio frequency amplifying networks, each consisting of a plurality of inductively coupled stages, and a stage of detection inductively coupled between the said networks, capacitative by-pass means coupled between the input and output circuits of each stage of the radio frequency amplifying network and between the inductive couplings of the same and that of the said stage of detection, and means including a reactance coupling said by-pass means to ground, each stage of audio frequency having a by-pass circuit to ground including a reactance of such value that undesired oscillations within the audio range are by-passed to ground.
